BY Robert O. Harris,
ATTORNEY

UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed October 7, 1925. Serial No. 61,098.

To all whom it may concern:

Be it known that I, MELVIN L. STONE, a citizen of the United States, and a resident of Lawrence, in the county of Essex and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for looms and is more particularly directed to means for maintaining the drop wires from lateral displacement or swinging movement during weaving.

In that type of warp stop mechanisms wherein the drop wires are normally supported by the warp threads during weaving, the lateral swinging movement of the drop wires frequently results in unreliable loom stoppage when a warp thread becomes broken or too slack and causes the drop wires throughout the entire series to come into close engagement, such that should a warp thread become too slack or be broken, the unsupported drop wire may not promptly move to stopping position, with the result that imperfect cloth is liable to be woven. In changing the warps in a loom, also, it is now frequently the practice to remove the old warp from the loom while the drop wires are still strung upon the warp threads and to hold the drop wires in close relation on the drop wire guides during their transportation to the "tying in" or "drawing in" machine.

One of the objects of the present invention, therefore, is to provide a warp stop mechanism of the type wherein the drop wires are normally supported by the warp threads during weaving with drop wire separators for dividing the series of drop wires into groups to overcome the tendency to lateral swaying movement, and yet permit the drop wires to be assembled in close relation during the transfer of the drop wires and old warp threads to the "tying in" or "drawing in" machines.

The novel features of the invention and new combination of parts will best be made clear from the following description and the accompanying drawings of one good form thereof.

In the drawings:

Fig. 1 is a perspective view with parts broken away, showing a warp stop mechanism containing the present invention;

Fig. 2 is a plan view showing two rows of drop wires with the drop wire separators and their separating relation thereto;

Fig. 3 is a cross-section of the warp stop mechanism showing the relation of the drop wires and drop wire separators; and

Fig. 4 is a section on the line 4—4 of Fig. 3, showing more particularly one good form of locking means for locking the drop wire separator rock shaft.

The warp stop mechanism is of that general type wherein a series of drop wires are normally supported by the warp threads between the shedding mechanism and whip roll during weaving, and, as shown, comprises the end frames 1 adjustably supported in position, as usual, by the bolts 2, only one of which is indicated in the drawings. Extending between the end frames 1 are the warp supporting bars 3 on which the warp threads α rest during the weaving operation and whereby they are enabled to properly support the drop wires in raised position.

In the present instance of the invention, two rows of drop wires 4, 4 are indicated for the purposes of description and each drop wire is provided with an elongated slot 5 through which pass the drop wire guides 6, the end portions of which are supported in bearings on the end frames 1, as indicated in Fig. 3. In order to maintain the drop wire guides 6 in their normal position during weaving, the end portions of the drop wire guides are held in position by cap plates 7 which may be conveniently secured in place by securing means such as the screws 8. The drop wires are each provided, in the present instance, with an opening 9 through each of which passes a warp thread α whereby the warp threads are enabled to normally support the drop wires in raised position during weaving. The present invention is not necessarily restricted to the particular form of drop wires indicated, but the characteristics and novel features of the invention may be advantageously employed with various forms of drop wires of which there are a number of well-known types.

Extending downwardly from the end

plates or brackets 1 are the portions 10 in which is supported for rocking movement the usual detector or feeler shaft 11 which may be suitably actuated from a going part 5 of the loom by means of an arm 12 and rod 13, such that during normal weaving operations the detector or feeler shaft is oscillated or rocked in its bearings, but when a warp thread breaks or becomes too slack for weaving purposes, the detector or feeler shaft is arrested in its movement, as usual, by means 10 of the detector bars 14, one of which contacts with the fallen drop wire and through any suitable means of any usual type well-known, the loom is brought to rest.

Mounted in parallel relation with the series of drop wires are the drop wire separator rock shafts 15, 16 which may be conveniently mounted in rocking bearings 17 20 carried by the warp supporting bars 3.

Each of the drop wire separator rock shafts 15, 16 carries a number of drop wire separators 18 adjustably mounted on each of the rock shafts for movement into desired 25 positions longitudinally thereof, in which position they may be secured by suitable means, such as the screws 19 which pass through the hub portions of the drop wire separators. Each of the drop wire separators, as shown, is preferably formed of a thin plate and constitutes a finger or projection extending from each of the rock shafts 15, 16 for insertion between the drop wires, while permitting the latter to remain substantially 30 in their proper separated relation transversely of the loom. In other words, the drop wire separators 18 are of plate formation, preferably made sufficiently thin not to interfere materially with the proper 35 location of the drop wires when inserted between them.

In order that the drop wire separators 18 may be simultaneously moved to and from their position between the drop wires, the 40 rock shafts 15, 16 are mounted for rocking movement and one, at least, is provided with manual means for turning the rock shaft, and where one only of such manual means is employed, the two rock shafts are connected 45 together for rocking movement in unison and in opposite directions. In the present instance of the invention, the rock shaft 15 is shown as provided with the crank arm 20 carrying the hand piece 21 whereby the rock shaft 15 may be manually turned in its bearings to move the separators 18 to and from their drop wire separating positions.

Each of the rock shafts is provided with a toothed segment 22 which are geared together, as shown, whereby rocking or turning movement of one shaft is imparted to the other shaft in an opposite direction, to thereby carry the drop wire separators of both shafts to and from their drop wire 55 separating positions.

As one good form of means for securing the toothed segments 22 to the respective rock shafts 15, 16, each segment 22 may be secured to its rock shaft by a hub portion 23 clamped to the rock shaft by a set screw 24, 70 and to obviate the necessity of unduly increasing the lateral dimensions of the warp stop mechanism provided with the present invention, the warp supporting bars 3 are each provided with a slot or opening 25, as 75 indicated in Fig. 4, whereby the segments 22 may be placed inside the adjacent end frame or bracket 1.

From the construction described it will be apparent that upon rocking movement of the 80 rock shaft 15 in its bearings, the drop wire separators of both shafts may be simultaneously moved to and from their positions separating the drop wires and maintaining them from lateral swaying movements, and when it becomes desirable to change the warp in the loom, a movement of one of the drop wire separator rock shafts will simultaneously move all of the drop wire separators from between the drop wires, thereby 85 permitting all the drop wires to be assembled in close contacting relation on the drop wire guides, in which position they may be held by tying the drop wires together for removal of the drop wires and old warp to the 90 tying in or drawing in machines.

When the drop wire separators have been moved either to or from their drop wire separating positions, it is desirable that they be locked in such position, and to this end 100 the hand piece 21 is provided with a locking pin 26 having a rounded or conical end portion 27 and normally pressed outwardly by a light spring 28 contained in a recessed hub or extension of the crank 20, as more 105 fully shown in Fig. 4. The end frame 1 adjacent the crank arm 20 is provided with an extension 29 having suitable recesses 30 for the reception of the rounded or conical end portion 27 of the locking pin 26, the construction being such that when the drop wire separator rock shafts have been moved into position with the drop wire separators between the drop wires, the locking pin 26 will act upon the entire series of drop wire 110 separators to maintain them in their drop wire separating positions, and conversely, when the drop wire rock shafts are turned to remove the drop wire separators from their separating positions to permit a change of the warp threads, as above described, the locking pin 26 by engagement with another recess in the projection 29 will maintain the drop wire separators in their inoperative 115 position, thereby permitting the drop wires to be assembled in close relation and tied together for a change in the warp threads.

When such change is to be effected, the cap plates 7 are released and turned back and the drop wires and drop wire guides may 120 125 130

be taken from the warp stop mechanism as a whole and transferred to the tying in or drawing in machine.

What is claimed is:

5. 1. In a warp stop mechanism for looms, the combination of a series of drop wires normally supported in raised position by the warp threads during weaving, warp supporting bars extending in parallel relation to the series of drop wires, a drop wire separator rock shaft mounted for rocking movement, a series of drop wire separators carried by the rock shaft, means for turning the rock shaft to move the drop wire separators between the drop wires, and a lock for holding the rock shaft in turned position.
10. 2. In a warp stop mechanism, the combination of a series of drop wires normally supported by the warp threads during weaving, a drop wire separator rock shaft, a series of drop wire separators carried by the rock shaft for insertion between the drop wires, and a lock for holding the rock shaft in position with the separators between the drop wires.
15. 3. In a warp stop mechanism, the combination of a series of drop wires normally supported by the warp threads during weaving, a drop wire separator rock shaft, a series of drop wire separators formed as thin plates carried by the rock shaft for insertion between the drop wires and a lock for holding the rock shaft in position with the separators between the drop wires.
20. 4. In a warp stop mechanism, the combination of a series of drop wires normally supported by the warp threads during weaving, a drop wire separator rock shaft, a series of drop wire separators mounted on the rock shaft for adjustment to different positions lengthwise thereof for insertion
25. between the drop wires, and means for turning the rock shaft to simultaneously insert the separators between the drop wires and remove them therefrom.
30. 5. In a warp stop mechanism, the combination of two series of drop wires normally supported by the warp threads during weaving, a drop wire separator rock shaft mounted adjacent each series of drop wires and provided with drop wire separators, operative connections between the two drop wire separator rock shafts that they may be rocked in unison, and means for rocking one of said shafts to insert and withdraw the separators of both shafts.
35. 6. In a warp stop mechanism, the combination of two series of drop wires normally supported by the warp threads during weaving, a drop wire separator rock shaft mounted adjacent each series of drop wires and provided with drop wire separators, operative connections between the two drop wire separator rock shafts that they may be rocked in unison, means for rocking one of said shafts to insert and withdraw the separators of both shafts, and a lock for holding the rock shafts with the separators inserted between the drop wires.
40. 7. In a warp stop mechanism, the combination of two series of drop wires normally supported by the warp threads during weaving, a drop wire separator rock shaft mounted adjacent each series of drop wires and provided with drop wire separators, gearing connecting the two rock shafts to cause them to simultaneously insert and withdraw the separators, and a lock for holding the rock shafts in turned position.

In testimony whereof, I have signed my name to this specification.

MELVIN L. STONE.
